UNITED STATES PATENT OFFICE.

JOHN J. RANGE, OF NORTHAMPTON, MASSACHUSETTS, ASSIGNOR TO THE BOSTON CASH REGISTER COMPANY, OF SAME PLACE.

CASH-REGISTER.

SPECIFICATION forming part of Letters Patent No. 479,335, dated July 19, 1892.

Application filed February 16, 1892. Serial No. 421,767. (No model.)

To all whom it may concern:

Be it known that I, JOHN J. RANGE, a citizen of the United States, residing at Northampton, in the county of Hampshire and State 5 of Massachusetts, have invented new and useful Improvements in Cash-Registers, of which the following is a specification.

In many cash-registers, as well known, there is comprised, in addition to a series of key-levers for operating the register and also on each registering operation thereof unlocking the cash-drawer, whereby it may be opened, a key-lever termed the "blank key," which has no connection with the register, but merely 15 unlocks the cash-drawer.

The object of this invention, which relates to cash-registering machines embodying a blank key, as explained, is to provide improved devices for special and sole action relative to 20 the blank key, whereby without respect to any of the register-keys that key may be locked against any swinging movement, said devices being capable of movement into disengaging relations with the blank key, and 25 to be so constructed that in any event and even should the locking device be in its location for engagement after the blank key has been swung into its position for unlocking the drawer, such key may be restored to its 30 normal position, no impediment to such restoring movement being constituted by the presence of the locking device, the latter, however, coming into engagement with the blank key immediately the key has come 35 into its normal position.

To this end the invention consists in the construction and combination of parts, all substantially as will hereinafter fully appear, and be set forth in the claim.

Referring to the accompanying drawings, Figure 1 is a perspective view and vertical section of a cash-register, showing a bank of register-operating key-levers and the blank key and in connection with the latter the 40 blank-key-locking device. Fig. 2 is a perspective view of the locking device.

It is to be understood that in the cash-register, partially shown in the drawings all of the key-levers *a*, which are shown as having

indicating-figures thereon corresponding to amounts represented by said key-levers, are in operative engagement with the register by the intervention of well-known mechanism, while the key *b* (shown at the front of the view) is entirely independent of the register- 55 ing mechanism and all as usual in registers of the type represented. All of the key-levers *a a* and *b* are arranged relative to the tilting plate *d*, so that as any one of the key-levers is swung the plate will be tilted, and, 60 through the link *f* and arm *e*, the shaft or bar *g* will be rocked. This rocking effects the swinging of the arm *h* and lifting of the bolt *j* from its latching engagement with the cash-drawer *B*. 65

The locking mechanism for the blank-key lever consists of a handle-bar *A*, mounted in a slideway formed on the end upright *x* of the frame for a bodily movement about horizontally forward and backward, and the pawl *m*, pivoted on the rear extremity of the said handle-bar and held by the spring *n* against the stop-pin *o* in an upwardly and rearwardly inclined position. The said slideway, as shown, consists of the parallel lips *i i*, the inner edges of which form the supports and guides for the pawl-carrying handle-bar, which latter has the longitudinal slot *q*, through which the screw *r* passes that enters, it is understood, to the frame and which by its 70 head or the washer *r²*, which is held thereby, on the outer face of the bar, prevents the outward displacement of the bar. 75

In Fig. 1 the pawl-carrying bar is shown in full lines as slid rearwardly, so that the pawl 85 is carried bodily beyond and out of engagement with the rear end of the blank key, while in the dotted lines the key-engaging relation of the parts are shown.

It will of course be understood that when 90 the blank-key lever is locked and the casing closed and locked there can be no access to the cash-drawer, except on the movement of the register-actuating levers *a*, which will only be when a cash-receipt is recorded and 95 the corresponding sum deposited in the drawer. Should the proprietor desire to operate the blank key for the purpose of open-

ing the drawer without actuating the register, this he can do after opening the casing by pushing back the bar, and at his option of course he can leave the machine so that 5 when the casing is locked any person can operate the blank key. Should the authorized person slide the bar rearward and then depress the forward end of the blank key, elevating the rear end thereof above the pawl 10 and then inadvertently forwardly return the pawl-carrying bar before the restoration of the blank-key lever to its normal position, the blank-key lever may nevertheless be restored to its normal position, for the rear end of the 15 lever will on its return movement impinge against what is relatively thereto the downwardly and forwardly inclined pawl-edge, swinging the pawl rearwardly until the lever passes it, when the pawl will snap to its interlocking position above the lever extremity. 20 Thus there can be no uncalled-for obstruction of the parts to normal positions, even when the greatest care and familiarity with the

construction is not had by the owner of the machine.

What I claim is—

In a cash-registering machine, the combination, with a cash-drawer and a locking device therefor, of a series of key-levers having an operative connection with the register and a blank-key lever, which, together with the register-key levers, is in operative connection with the cash-drawer-locking device, and a handle-bar mounted for a sliding movement forward and back on a stationary support which 30 is adjacent the blank key, and said handle-bar having thereon a pivoted pawl located in a plane coincident with the course of movement of the blank-key lever, which is held normally forwardly spring-pressed and which 35 has an upward and rearward inclination, substantially as and for the purposes set forth.

JOHN J. RANGE.
